UNITED STATES PATENT OFFICE.

WILLIAM I. BUNKER, OF LA GRANGE, ILLINOIS.

DESIGN FOR A BICYCLE-SADDLE.

SPECIFICATION forming part of Design No. 24,877, dated November 12, 1895.

Application filed October 11, 1895. Serial No. 565,422. Term of patent 7 years.

To all whom it may concern:

Be it known that I, WILLIAM I. BUNKER, a citizen of the United States, residing at La Grange, Cook county, Illinois, have invented and produced a new and original Design for 5 Bicycle-Saddles, of which the following is a specification, reference being had to the accompanying drawings, forming a part hereof.

In the accompanying drawings, Figure 1 10 represents a plan view of my design, looking at it from the top; and Fig. 2, a transverse section taken on the line 2 of Fig. 1.

The leading feature of my design consists in a body portion for a saddle, provided with 15 semicircular - curved ends joined together near the center, so that when viewed in plan

view, as in Fig. 1 of the drawings, it will present to the eye an outline resembling somewhat the letter B or D.

A is the body portion of the saddle; a, the 20 semicircular ends joined together at a'.

In the sectional view, B is the supporting frame, b the sustaining-socket, and b' a set-screw by which it may be secured in any desired position. 25

What I claim is—

The design for a bicycle saddle herein shown and described.

WILLIAM I. BUNKER.
